Attest,

UNITED STATES PATENT OFFICE

EDWARD D. DAVIS, OF CHICAGO, ILLINOIS, ASSIGNOR TO THE BOYE NEEDLE COMPANY,
OF CHICAGO, ILLINOIS, A CORPORATION OF ILLINOIS

HAIRPIN

Application filed July 31, 1931. Serial No. 554,308.

This invention relates to clip hairpins. It constitutes, in some respects, an improvement upon the type of hairpin described in my Patent No. 1,752,893.

5 An object of the invention is to provide a clip hairpin of simple and sturdy construction which cannot easily be dislodged and which holds the body of the pin concealed within the hair.

10 With clip hairpins heretofore used, there has been a tendency for the pin to engage a lock of hair along an intermediate point of the pin and the pin tends to rock upon the lock of hair so that one end or the other of 15 the hairpin protrudes from the hair. With my improved form of hairpin, the pin is locked to the hair at the free extremities of its legs and the pin is thus securely retained within the hair. Also, the improved form of 20 hairpin tends to conform to the head of the wearer and lies snugly in position. A further object is to provide hair-engaging 25 serrations or knurling which cooperate with the structure of the pin to hold the pin in place. Other objects and advantages will appear as the specification proceeds.

The invention is illustrated, in its preferred embodiment, in the accompanying drawings, in which—

30 Figure 1 is a plan view of the inner face of the hairpin before the pin has been crimped and bent to place it in finished condition; Fig. 2, a side view of the pin in the form illustrated in Fig. 1; and Fig. 3, an enlarged 35 side view of the finished pin after the bending and crimping operation.

In the illustration given, 1 designates a loop or bent portion, and 2 and 3 the lower and upper legs of the pin which are formed 40 integrally with the loop 1. The lower leg 2 is substantially straight throughout the greater extent of its length, but is curved downwardly along its front tip portion 4. The forward half portion of the upper leg 3 45 is crimped or provided with waves at 5. The upper leg 3 is also provided with a downwardly curved tip portion 6 which contacts with the tip portion 4 of the lower leg 2.

Either or both of the legs may be provided 50 on their inner surfaces with knurling or hair-

engaging serrations. In the illustration given, both of the hair clasping members 2 and 3 have their inner surfaces superficially roughened or knurled as indicated at 7. The roughened surfaces 7 engage individual hairs and the individual hairs serve as wedges to lock entire strands of hair in the pin.

55 The downwardly curved tip portions 4 and 6 of the hair clasping members 2 and 3 are preferably so formed as to enable these portions of the pin to rest snugly against the head of the wearer. Also, their contacting inner surfaces serve to engage strands of hair and thus anchor the front end of the pin well 60 within the hair. With the front end of the 65 clip hairpin securely tied in position, and with the body of the pin secured by means of the roughened surfaces 7 to locks of hair, the pivotal or rocking action of the hairpin, heretofore mentioned, is avoided, the entire 70 pin remaining in its initial position in the hair.

75 The foregoing detailed description has been given for clearness of understanding only and no unnecessary limitations should be understood therefrom, but the appended claims should be construed as broadly as permissible in view of the prior art.

I claim:

1. A clip-hairpin comprising a loop and 80 inner and outer hair-clasping members extending from said loop and provided at their free extremities with substantially parallel in-curves having superficially roughened adjacent surfaces.

85 2. A clip-hairpin comprising a loop and inner and outer hair-clasping members extending from said loop, the inner member having a substantially straight portion extending from the loop and an in-curved end portion, the clasping surface of said inner member being superficially roughened throughout its straight portion and curved portion, and the outer member having a 90 crimped portion overlying the straight portion of the inner member and a curved end portion overlying the curved end-portion of the inner member, the clasping surface of the outer member being roughened throughout 95 100

the crimped portion and the curved extremity thereof.

3. A clip-hairpin comprising a loop and inner and outer hair-clasping members extending from said loop and provided at their free extremities with substantially parallel in-curves having their adjacent surfaces in contact, at least one of said surfaces being superficially roughened.

4. A clip-hairpin comprising a loop and inner and outer hair-clasping members extending from said loop and provided at their free extremities with substantially parallel in-curves having their adjacent surfaces in contact, at least one of said hair-clasping members having a portion of its inner surface superficially roughened.

EDWARD D. DAVIS.
